UNITED STATES PATENT OFFICE.

CHARLES H. SANBORN, OF NEWBURYPORT, MASSACHUSETTS.

SEWING-MACHINE BINDER GUIDE.

Application filed June 30, 1924. Serial No. 723,173.

To all whom it may concern:

Be it known that I, CHARLES H. SANBORN, a citizen of the United States, and resident of Newburyport, in the county of Essex and State of Massachusetts, have invented an Improvement in Sewing-Machine Binder Guides, of which the following is a specification.

In the operation of straight needle sewing machines in binding the edges of upper leather for shoes with a galloon, or tape, where the galloon is simply bent about the edge of the leather onto both sides, and attached by stitches which pass through the opposite portions of the galloon and the intervening leather, it is customary to vary the extent to which the edge portion of the galloon laps onto the outer side from a width equal to approximately half the total width of the galloon to a width which is the least possible which can be turned over thereon and stitched. In performing this operation, it is customary to provide the machine with an attachment for folding the galloon longitudinally about the edge of the leather and hold it in position while it is being secured by the stitches. The form of attachment most generally employed for this purpose is known as a strip reversing binder guide and comprises an arm having a transversely curved throat and a transversely concave guiding and folding groove, at right angles thereto, so that the fold formed in the strip, as it is drawn through the throat, is reversed as it is drawn against the bottom of the groove. Prior to my invention, it has been customary to provide attachments of some six different forms of guiding and folding grooves for use according to the width of galloon to be turned over onto the face side of the leather.

The object of my invention is to provide a form of attachment of the above described type and for the above described purpose which is provided with an improved means for guiding and controlling the extent to which the galloon is laid onto the other side of the leather, which is adapted for adjustment, so that this extent may be varied within the desired limits, whereby a single attachment may be made to perform the work of the several different attachments which have previously been employed.

I accomplish this object by means of the construction hereinafter described and il-

lustrated in the accompanying drawing, in which:

Fig. 1 is a plan view of a sewing machine attachment containing a preferred embodiment of my invention and shown in position on a sewing machine table.

Fig. 2 is a perspective view thereof.

Figs. 4 and 5 are detail views of the two main parts of the attachment.

Figs. 6 and 7 are enlarged detail views showing different adjustments of the attachment.

Fig. 8 is a longitudinal sectional view of the attachment on an enlarged scale.

Fig. 9 is a perspective view, illustrating the operation of guiding the galloon into position for attachment.

As shown in the drawing, the main body of the attachment is similar to that now generally employed for the purpose above described, and comprises an arm *a* which is adapted to be clamped on the machine table by a thumb-screw *b* passing through a slot *c* in the arm to permit adjustment thereof, said arm having a semi-circularly shaped groove *d* in its end which extends transversely of the arm in the direction of the feed of the machine, the arm being set at right angles to the feed. The front edge of the arm has a longitudinal, transversely convex rib *e* on its front edge, which is enclosed by a semi-casing *f* at its front end to form a semi-annular passage *g* through which the galloon *x* is fed after passing between the tension fingers *h*. With this arrangement the galloon is bent convexly at its front side as it emerges from the passage *g* and is then drawn sharply at right angles into the semi-circular groove *d*, so that it will be bent oppositely and lie against the bottom of said groove. The leather about the edge of which the galloon is to be laid is so held that its edge is pressed against the bottom of the groove at the middle thereof, and the galloon is thus bent over onto both sides of the leather and about its edge. The sewing machine needle *i* operates close to the rear side of the arm *a*, so that the galloon is stitched in the position in which it is held. Prior to my invention, the extent to which the galloon lies over onto the face side of the leather has depended on the formation of the end groove *d* and with the construction shown the galloon will be folded along the middle,

so that it will extend about equally onto the top and bottom sides.

According to my invention, I provide a gage finger *j* which is adapted to be secured 5 on the upper side of the arm *a* by means of a thumb screw *k* which passes through an elongated hole *m* therein, to permit adjustment of the finger longitudinally. The finger is provided with a vertically depending edge gage *n* which extends at right angles to the finger *j* and when the latter is in position on the arm *a* depends into the groove *d* a short distance beneath its upper side, the edge portion of said upper side 10 having a slot or notch *o* therein, in which said edge gage is located. Said slot is of sufficient length to permit the necessary longitudinal adjustment of the finger and acts to hold said finger from swinging out of 15 position. A foot *p* is integrally, or otherwise permanently connected to the lower end of the edge gage at right angles thereto, said foot being arranged to project horizontally beyond each side of the edge gage 20 providing a work engaging face *p*¹ at its upper side and a guiding face *p*² at its upper side and at the inner side of the edge gage. The front end of the foot *p* is upturned and extends in front of the front 25 side of the arm *a*.

In operation the galloon is drawn through the passage *g* and at right angles against the bottom of the groove *d* as before described, so 30 that it is partly folded longitudinally, one edge portion being drawn against the under side of the groove and the other against the upper side thereof. The edge gage *n* depends below the upper side of the groove *d*, to such an extent that the face *p*², on 35 upper inner side of the foot *p*, is held at a distance from the upper side of the groove which is somewhat greater than the thickness of the galloon and the arrangement is such that as the galloon is drawn rearward, 40 its upper edge portion will be drawn into the space between said face *p*² and the upper side of the groove *d* with its edge in abutment with the inner or adjacent side of the edge gage *n*. The transverse position of 45 the galloon in the groove is thus determined by the position of the edge gage *n*. The leather, to which the edge binding is to be 50 applied, is placed between the under face *p*¹ of the foot *p* and the lower edge portion 55 of the galloon, which is resting on the lower side of the groove *d*, the edge of the leather being pressed against the bottom of the groove and its upper side being held close 60 to or against the under face *p*¹ of the foot *p*, while its under side lies on the portion 65 of the galloon which rests on the under side of the groove *d*. The galloon will thus be laid about the edge of the leather and will be fed to the needle in this position. The position in which the galloon will be held

with relation to the leather will depend on the extent which the edge gage *n* permits the galloon to overlap the leather on its upper side, and this will depend on the transverse adjustment of the edge gage 70 with relation to the bottom of the folding groove *d*. That is, the nearer the gage is adjusted to the bottom of the groove, the narrower will be the portion of the galloon which will be permitted to lie on the upper side of the leather as it is fed to the needle. This adjustment is readily secured by loosening the screw *k* and adjusting the finger *j* longitudinally. The same result is thus secured with one attachment as would be secured by a series of similar devices having folding grooves of different shapes. Moreover my improved construction more effectively and accurately guides the galloon than said prior devices, as the foot *p* operates in conjunction with the edge gage *n*, to support the inwardly projecting edge portion of the galloon, so that its edge is held against the gage as it is drawn past the same. 90

I claim:

1. A strip reversing binder guide for sewing machines having a longitudinally extending transversely curved guiding throat, and a transversely concave folding groove extending transversely of the end of the arm in the direction of the sewing machine feed, and adapted to fold a strip longitudinally as it is drawn therethrough, a finger mounted on said arm and having an edge gage depending from the upper side of said groove in position to be engaged by the uppermost edge of the longitudinally folded strip as it is drawn through said groove, and to determine the transverse position of the strip in the groove and the extent to which it will overlap the upper side of the work. 105

2. A strip reversing binder guide for sewing machines having a longitudinally extending transversely curved guiding throat, and a transversely concave folding groove extending transversely of the end of the arm in the direction of the sewing machine feed, and adapted to fold a strip longitudinally 110 as it is drawn therethrough, an edge gage mounted on said arm and having a portion thereof depending in front of said groove from the upper side thereof in position to engage the uppermost edge of the longitudinally folded strip as it is drawn against the bottom of the groove, and means permitting adjustment of said gage to and from the bottom of said groove to vary the transverse position of the strip therein and determine the extent to which it will overlap the upper side of the work. 125

3. A sewing machine binder guide comprising an arm having a transversely concave groove therein arranged to extend hori- 130

- zontally transversely of the end thereof in the direction of the sewing machine feed, and having means whereby a strip of gal-
loon will be folded longitudinally as it is
5 drawn therethrough, said groove having a slot extending through its upper side trans-
versely thereof, a finger mounted on the upper side of said arm for adjustment longitudinally thereof and having an edge gage at
10 its end depending through said slot in position to engage the uppermost edge of the transversely folded galloon as it is drawn through said groove.
4. A sewing machine binder guide com-
15 prising an arm having a transversely con-
cave groove therein arranged to extend hori-
zontally transversely of the end thereof in the direction of the sewing machine feed, and having means whereby a strip of gal-
20 loon will be folded longitudinally as it is drawn therethrough, an edge gage mounted on said arm arranged to depend into said groove in position to engage and guide the uppermost edge of the galloon as it is drawn
25 through said groove, a foot piece on the lower end of said edge gage and having a portion thereof projecting therefrom to-
wards the bottom of said groove, to support the edge portion of the galloon engaged by said edge gage and means permitting ad-
justment of said edge gage to and from the bottom of said groove.
5. A sewing machine binder guide com-
30 prising an arm having a transversely con-
cave groove therein arranged to extend hori-
zontally transversely of the end thereof in the direction of the sewing machine feed, and having means whereby a strip of gal-
loon will be folded longitudinally as it is drawn therethrough, an edge gage mounted on said arm arranged to depend into said groove in position to engage and guide the uppermost edge of the galloon as it is drawn through said groove, and a foot piece on the lower end of said edge gage having a face 45 on its under side for engagement with the material to which the galloon is to be attached and having a portion projecting towards the bottom of the groove from the inner side of said edge gage to support the upper edge portion of the galloon while engaged by said edge gage.

In testimony whereof, I have signed my name to this specification.

CHARLES H. SANBORN.
